UNITED STATES PATENT OFFICE.

LELAND S. ROSENER, OF SAN FRANCISCO, CALIFORNIA, ASSIGNOR TO THE PARAFFINE COMPANIES, INC., OF SAN FRANCISCO, CALIFORNIA, A CORPORATION OF DELAWARE.

WINDING APPARATUS.

Application filed March 27, 1920. Serial No. 369,233.

To all whom it may concern:

Be it known that I, LELAND S. ROSENER, a citizen of the United States, and a resident of the city and county of San Francisco and State of California, have invented a new and useful Winding Apparatus, of which the following is a specification.

My invention relates to apparatus for winding webs into rolls.

One of the objects of the invention is to provide an apparatus for quickly winding up into rolls, lengths of web delivered to it, and especially lengths of roofing fabric as it issues from an automatic roofing machine. Another object is the provision of an apparatus of the character described in which improved means are provided for the control of the arbors on which the webs are wound. Another object is the provision of an apparatus of the character described in which neither operator can rotate the arbor on which the other operator is working.

Since a machine for preparing roofing at high speed would be useless unless the webs of finished roofing can be made up into packages and orderly disposed of, it follows that the capacity of the roofing machine may be expressed in terms of the capacity of the winding devices to handle the finished roofing. Therefore it is the broad object of my invention to provide a winding apparatus capable of being operated at high speed so that webs of finished roofing issuing from the automatic roofing machine may as fast as it is produced, be inspected, formed into rolls, wrapped, weighed and thrown onto a conveyor to be carried to a storage or shipping room.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

In the drawings, Figure 1 is an elevation of the winder. Figure 2 is a plan view of a portion of the winder showing the pneumatic cylinders and related parts. Figure 3

is a vertical section taken in the plane indicated by the line 3—3 of Figure 2. Figures 4 and 5 are elevations of parts of the switch shown in plan in Figure 2. Figure 6 is a sectional view through the driving gear of one of the arbors. Figure 7 is a vertical section taken in the plane indicated by the line 7—7 of Figure 1. Figure 8 is a side elevation partly in section of the pneumatically operated means for blocking the rolls when the arbors are withdrawn to unload the rolls; and Figure 9 is a front elevation of the same. Figure 10 is a vertical section through the control post. Figure 11 is a section through the valve controlling the pneumatic cylinders shown in Figures 8 and 9. Figure 12 is a plan view of the link connection between the control rods and the valve. Figure 13 is a diagrammatic view of the pneumatic cylinders and their controls. Figure 14 is a vertical sectional view through the valves controlling the passage of air to the pneumatic cylinders associated with the arbor shifting means. Figure 15 is a diagram of the electrical circuits for controlling the means for rotating the winding arbors.

In terms of broad inclusion, the winding apparatus of my invention comprises two winding arbors on which the operator alternately directs the winding of rolls. While one roll is being wound by the operator, the previously formed one is being wrapped and then unloaded by a second operator who stands to one side. Manually controlled means are provided for shifting each arbor axially from the winding or loading position to the wrapping or unloading position and vice versa, and also for rotating the arbors in either position. Automatically operating means are provided for preventing either operator causing the rotation of the arbor on which the other is working. Manually controlled means are also provided for blocking the movement of the wrapped roll when the arbor is withdrawn from it on its return to winding or loading position, so that the roll drops upon a scale where its weight is noted.

Rotatably and slidably journaled in main frame members 1 and 2 are arbors 3 and 4 upon which the web 6 is formed into rolls, such as roll 7 shown on arbor 3.

A jack shaft 8 journaled in the frame

members carries a fixed pulley 9 which is belt driven from any suitable source of power. Surrounding the arbor 3, is a flanged sleeve 11, Figure 6, journaled in 5 suitable bearings set in the frame. A spline 12 on the arbor fixes the arbor and sleeve for rotation together, but permits the arbor to be moved axially. The sleeve is formed with a spur gear 13 in mesh with spur gear 14, 10 forming part of the driven member of magnetic clutch 16 of known form, the driving members of which are fixed on the shaft 8. At the other end of the shaft 8, a second magnetic clutch 17 is arranged, its gear 18 15 meshing with gear 19 on sleeve 21 which is journaled in frame 1 and in which arbor 4 is splined. Thus both arbors are mounted for axial and rotary movement and are rotated, each through its own clutch, by the 20 shaft 8.

Rotatably fixed on the end of arbor 3 is a sleeve 22 having trunnions 23 thereon. Boxes 24 are journaled on the trunnions, and slidably engaging the boxes is the bifurcated end of a lever 26. The lower end of 25 the lever is mounted for pivotal movement about a fixed pivot 27, and intermediate its ends a short rod 28 connects the lever with a cross head 29 mounted in slides 31. The cross head is reciprocated to vibrate the lever by a piston rod 32 and pistons, arranged in cylinder 33. The arbor 4 is similarly operatively connected to piston rod 34 of cylinder 36 by means of lever 37, connecting rod 38, and cross head 39.

Each of the cylinders 33 and 36 are connected by suitable conductors to an air tank. Manually controlled valves are arranged in 40 the conductors so that the pistons may be operated as desired to axially shift the arbors. Figures 10, 13 and 14 considered in connection with Figure 1 will make this mechanism clear. A control post 41 is fixed in a convenient position between the two 45 operators and contains a rod 42 turned by handle 43, and sleeve 44 turned by handle 46. The lower end of the rod 42 is fitted with a lever arm 47 connected by a link 48 to the lever arm 49 of the rocker shaft 51 which actuates the slide valve 52 in the valve casing 53. The valve 52 controls the distribution of air under pressure to the conductors 54 and 56, connecting the valve chamber with the ends of the cylinder 58. The valve casing is connected by conductor 57 with the supply main 58. The lower end of the sleeve 44 is provided with 55 a lever arm 61 connected by link 62 to a second valve mechanism in valve casing 63 connected by conductors 64 and 66 to the ends of cylinder 33. Thus by movement of the handles 43 and 46 air under pressure is admitted as desired to the cylinders 33 and 36 to axially shift the arbors from loading 60 to unloading position and vice versa.

Means are provided for enabling each operator to control the rotation of the arbors, but such control means are so arranged that neither operator can control the rotation of the arbor on which the other is working. That is to say, the operator who is attending the winding up on arbor 4, of the roll from web 6, Figure 1, cannot start or stop the arbor 3 bearing the roll 7, which has been shifted to the second operator and is 70 about to be wrapped and dismounted or unloaded from the arbor; neither can the second operator control the rotation of either arbor when the roll is being wound up on it. On the frame 68 supporting the pneumatic cylinders 33 and 36 and the slides for the cross heads 29 and 39, are switches 69 and 71 on one side and 72 and 73 on the other. Each comprises contact points 74 spaced apart on spring arms 76 and insulated therefrom. Fixed on cross head 39 is a circuit closer comprising a block 77 of insulating material, shod on the ends with metallic shoes 78 adapted to wedge between the contacts 74 at the end of each stroke of the cross head to close the circuit between them. 85

In a convenient position adjacent the frame 2, are manually operated switches 79 and 81, for the control of the magnetic 90 clutches by the first operator. In Figure 15, the circuits for the control of the clutches are shown in diagram. Switch 79 is placed in conductor 82 which connects main line 83 with one contact 74 of switch 72. The other contact of this switch is connected to the clutch 16 by conductor 84, the other side of the circuit to the clutch being formed by main line conductor 86. That is, switches 79 and 72, and the clutch 16 are all in series 105 in the circuit 82—86. Switch 81 is placed in conductor 87 connecting main line 83 with one contact 74 of switch 69. The other contact of this switch is connected by conductor 88 with clutch 17, the other side of the clutch 110 being connected into main line 86. It will be seen that switches 69 and 72 are closed only when the cross heads 39 and 29 respectively are drawn back to their extreme positions near the cylinders, at which time only 115 do the shoes 78 bridge the gap between the contacts 74 on the switches. That is, the switches are closed only when the arbors are drawn back to the loading or winding positions, and with the initial axial movement of the arbors these circuits are broken. Hence it is only while the arbors are in the loading position that manually operated 120 switches 79 and 81 are effective.

When an arbor bearing a roll, (such as 125 7 in Figure 1) is moved to unloading position, it is necessary to rotate it in order to properly apply the wrapper. For this purpose a spring pressed foot switch 89 is provided which controls the rotation of either 130

arbor which is in the unloading position. This switch is inserted in line 91 which connects main line 83 through one branch 91^a with one contact 74 of switch 73, the other contact being connected by conductors 92—84 to clutch 16. The other branch 91^b connects line 91 with one contact 74 of switch 71, the other contact of this switch being connected by conductors 93—88 to clutch 17. Switch 89 is therefore ineffective unless switch 71 or 73 is closed, and these are closed only when the associated arbor is moved outwardly to the unloading position.

Thus, a roll 7 being complete, say on arbor 3, the first operator moves the lever 46 on the control post to admit air to the cylinder 33. The cross head 29 and lever 26 move to the positions shown in Figures 1 and 2, axially moving the arbor to position the roll in front of the second operator. With the first axial movement of the arbor, the circuit through switch 72 is broken throwing out clutch 16 and permitting the roll and arbor to stop rotating. As the arbor reaches the end of its stroke, the switch 73 is closed, but the circuit is still open at floor switch 89. The second operator presses this switch with his foot as rotation of the roll is required in applying the wrapper. On return of the arbor to loading position, switch 73 is opened and switch 72 closed at the end of the return stroke, operating the clutch to again rotate the arbor, unless in the meantime the first operator has opened switch 79. In ordinary operation switch 79 remains closed so that on the return of the arbor to loading position the clutch is automatically operated to rotate the arbor.

Means are provided for stripping the rolls from the arbors as they are returned to loading position. A second control post 94 is arranged convenient to the second operator, and handles 96 and 97 arranged thereon. Each of these handles is connected, by means already explained in connection with the control post 41, to a lever arm 98 for operating a valve 99, Figures 8, 11 and 12. One of these valves is arranged to control the flow of compressed air to and from the lower end of each of the cylinders 101 and 102, arranged below the arbors. In each cylinder a piston is disposed on which is a rod 103 capped with a head 104 having a recess therein adapted to engage about the arbor. The piston rods are prevented from turning, and thus misaligning the heads with the arbors, by means of a spline 106 arranged thereon. When the roll 7 is wrapped and the second operator desires to unload it from the arbor, he turns handle 96, Figures 1 and 13, which opens the valve 99 associated with cylinder 101. The piston rod then rises seating the head 104 under the arbor 3. The operator next throws over

lever 46 which admits air into cylinder 33 65 to retract the arbor 3 to loading position, drawing it out of the roll 7, the movement of which is blocked by the head 104. The roll then drops upon the platform of a scale so that its weight may be ascertained. 70 As soon as the roll is free from the arbor, the operator turns the handle 96 back to first position which permits the air in the cylinder to exhaust through the vent 107.

I claim:

1. In an apparatus for winding a web into a roll, an arbor, means for rotating the arbor, a clutch interposed in said rotating means, means for axially shifting the arbor from loading to unloading position and vice versa, means adjacent the arbor in each position for controlling the operation of said clutch, and means for rendering inoperative said controlling means at each position when the arbor is in the other position. 85

2. In an apparatus for winding a web into a roll, an arbor, means for rotating the arbor, an electrically operated clutch interposed in said rotating means, means for axially shifting the arbor from loading to 90 unloading position and vice versa, an electric circuit for controlling said clutch when the arbor is in the loading position, an electric circuit for controlling said clutch when the arbor is in the unloading position, and 95 means for opening the circuit controlling the clutch in each position of the arbor when the arbor shifts to the other position.

3. In an apparatus for winding a web into a roll, an arbor, means for rotating the arbor, an electrically operated clutch interposed in said rotating means, means for axially shifting the arbor from loading to unloading position and vice versa, an electric circuit for controlling said clutch when 100 the arbor is in the loading position, an electric circuit for controlling said clutch when the arbor is in the unloading position, and means operated by the arbor shifting means for opening the circuit controlling the clutch 105 in each position of the arbor when the arbor shifts to the other position. 110

4. In an apparatus for winding a web into a roll, an arbor, means for rotating the arbor, an electrically operated clutch interposed in 115 said rotating means, means for axially shifting the arbor from loading to unloading position and vice versa, an electric circuit for controlling said clutch when the arbor is in the loading position, an electric circuit 120 for controlling said clutch when the arbor is in the unloading position, and means operated automatically in time with the initial shifting movement of the arbor for opening the circuit controlling the clutch in each 125 position of the arbor when the arbor shifts to the other position.

5. In an apparatus for winding a web into

a roll, an arbor, pneumatic means for axially shifting the arbor from loading to unloading position and vice versa, means for rotating the arbor, a clutch interposed in said rotating means, and means adjacent each position of the arbor for exclusively controlling the operation of said clutch when said arbor is in that position.

6. In an apparatus for winding a web into a roll, an arbor, means for rotating the arbor, a lever pivotally and rotatably connected with the arbor, and a pneumatically operated piston for moving said lever to shift said arbor.

15 7. In an apparatus for winding a web into a roll, an arbor, means for rotating the arbor, a lever pivotally and rotatably connected with the arbor, a pneumatically operated piston for moving said lever to shift said arbor from loading to unloading position and vice versa, a clutch interposed in said arbor rotating means, means for controlling the operation of said clutch adjacent the arbor in each position, and means operated in time with the movement of said piston for rendering inoperative said controlling means at each position when the arbor is in the other position.

8. In an apparatus for winding a web into a roll, an arbor, means for rotating the arbor, a lever pivotally and rotatably connected with the arbor, a pneumatically operated piston for moving said lever to shift said arbor from loading to unloading position and vice versa, an electrically operated clutch interposed in said arbor rotating means, a pair of electric circuits for controlling said clutch, and means operated by said piston for opening one and closing the other of said circuits with each stroke.

9. In an apparatus for winding a web into a roll, an arbor, means for rotating the arbor, a pneumatically operated piston meditately connected to said arbor for shifting the arbor axially, an electrically operated clutch interposed in said arbor rotating means, a pair of electric circuits for controlling said clutch, and means operated by said piston for opening one and closing the other of said circuits with each stroke.

10. In an apparatus for winding a web into a roll, an arbor, means for rotating the arbor, a pneumatically operated piston meditately connected to said arbor for shifting the arbor axially, an electrically operated clutch interposed in said arbor rotating means, a pair of electric circuits for controlling said clutch, means operated by said piston for opening one and closing the other of said circuits with each stroke, and means inde-

pendent of said piston for opening and closing said circuits.

11. In an apparatus for winding a web into a roll, an arbor on which the web is wound, means for rotating the arbor, means for axially shifting the arbor from the loading to the unloading position and vice versa, and means for blocking the movement of the roll when the arbor is shifted from the unloading to the loading position.

12. In an apparatus for winding a web into a roll, an arbor on which the web is wound, means for rotating the arbor, means for axially shifting the arbor from the loading to the unloading position and vice versa, and pneumatically operated means for blocking the movement of the roll when the arbor is shifted from the unloading to the loading position.

13. In an apparatus for winding a web into a roll, an arbor on which the web is wound and movable axially from the loading to the unloading position, means for rotating the arbor, a lever pivotally and rotatably connected at one of its ends with the arbor and movable about a fixed pivot at the other end, a cross head attached to said lever, a pneumatically operated piston connected to said cross head, an electrically operated clutch interposed in said arbor rotating means, a pair of electric circuits for controlling said clutch, means on said cross head for opening one of said circuits at the beginning of each stroke and closing the other of said circuits at the end of each stroke, independent means for opening and closing said circuits and means for blocking the movement of the roll when the arbor is shifted from the unloading to the loading position.

14. In an apparatus for winding webs into rolls, a pair of arbors on which the rolls are wound, means for axially shifting the arbors from the loading to the unloading position and vice versa, means for rotating the arbors, an electrically operated clutch interposed in both said rotating means, an electric circuit for controlling each clutch when the associated arbor is in the loading position, a manually operated switch in each circuit, an electric circuit for controlling each clutch when the associated arbor is in the unloading position, a switch for simultaneously controlling both said last named circuits, and means operated by each of said axial shifting means for opening one of the associated circuits and closing the other with each stroke.

In testimony whereof, I have hereunto set my hand.

LELAND S. ROSENER.
